UNITED STATES PATENT OFFICE.

OTTO NEWLIN, OF WALLACE, MICHIGAN.

LOG LOADING AND UNLOADING GRAPPLE.

Application filed April 29, 1921. Serial No. 465,448.

To all whom it may concern:

Be it known that I, OTTO NEWLIN, a citizen of the United States, residing at Wallace, in the county of Menominee, State of Michigan, have invented certain new and useful Improvements in Log Loading and Unloading Grapples; and I do hereby declare the following to be a full, clear, and exact description of the invention, such as 10 will enable others skilled in the art to which it appertains to make and use the same.

This invention relates to new and useful improvements in load handling devices and particularly to devices for handling loads 15 of logs.

In handling pulp wood logs, the logs are loaded on a sled or truck, and a chain passed around the logs and secured thereround. This consumes time. When the logs are to 20 be lifted from the sled or truck and deposited on a car, it is necessary to remove the chain from the logs. This also consumes time, as well as labor.

It is the particular object of the present 25 invention to provide a device whereby the use of chains is rendered unnecessary, the logs being loaded on the sled in the usual manner, and when the logs are to be removed and lifted to a car, by means of a crane or 30 derrick, the entire load can be grasped, lifted from the sled, and quickly released when deposited onto the car.

Other objects and advantages will be apparent from the following description when 35 taken in connection with the accompanying drawing.

In the drawing:

Figure 1 is a perspective view of the grapple, in gripping engagement with a bundle 40 of logs.

Figure 2 is a perspective view of the grapple in open position.

Referring particularly to the accompanying drawing, 10 and 11 represent a pair of 45 oppositely bowed legs having their upper ends pivotally connected together, as shown at 12. Extending upwardly from each bowed leg, above the pivot 12, is a shank 13 having an eye 14 for attachment of the 50 lifting chains 15.

The free end of the bowed leg 10 is bifurcated, as shown at 16, to receive therein the single strand end 17 of the leg 11, when the

legs are engaged around the bundle of logs, as seen on the drawing, in Figure 1. By 55 this construction the single strand end is prevented from lateral movement, with respect to the end of the other leg, thus firmly and positively gripping and holding the bundle of logs, while being lifted and transferred to a car.

Connected to the bifurcated end 16, and to the eye 14, at that side of the grapple, is a chain 18 which is adapted to be grasped by the operator on the car, to pull the legs apart 65 and release the bundle of logs. It will be noted that upon pulling outwardly on the chain 18, the lower end thereof pulls the leg 10 away from the leg 11, while the upper end pulls the eye of the leg 11, and thus 70 swings this latter leg away from the first leg; with the result that both legs are simultaneously withdrawn from beneath the bundle of logs, and the logs permitted to drop onto the car, or logs previously deposited in 75 the car.

There is thus provided a novel, simple, and efficient device, whereby loads of pulp wood logs can be easily and quickly handled, and without the waste of time and labor in 80 securing and releasing the usual chain load binders.

What is claimed is:

A grapple for pulp wood logs comprising 85 a pair of crossed and pivoted outwardly bowed log bundle gripping legs, the portions of the legs above the pivot being provided with chain receiving eyes, the lower end of one of the bowed legs being formed of a single strand, the lower end of the other 90 leg being bifurcated for the reception therein of the end of the first leg whereby the said ends of the legs are prevented from lateral movement with respect to each other, and a releasing chain connected with the 95 bifurcated leg and the eye of the other leg for simultaneously moving the legs away from each other to release a bundle of logs.

In testimony whereof, I affix my signature, 100 in the presence of two witnesses.

OTTO NEWLIN.
